UNITED STATES PATENT OFFICE.

CHARLES E. CARROLL, OF NEWPORT, ARKANSAS.

DESIGN FOR A TOOTH-BRUSH.

44,997.

Specification for Design.

Patented Dec. 9, 1913.

Application filed September 23, 1913. Serial No. 791,437. Term of patent 14 years.

To all whom it may concern:

Be it known that I, CHARLES E. CARROLL, a citizen of the United States, residing at Newport, in the county of Jackson, in the State of Arkansas, have invented a new, original, and ornamental Design for Tooth-Brushes, of which the following is a specification, reference being had to the accompanying drawing, forming part thereof.

Figure 1 of said drawing is a side view

of a tooth-brush showing my new design, and Fig. 2 is an end view of the same.

I claim:

The ornamental design for a tooth-brush as shown.

CHAS. E. CARROLL.

Witnesses:

E. A. HIRSCH,
S. C. MACK.
